FIG. 1 is a top plan view of a roofing clip showing my new design.

FIG. 2 is a side view of the roofing clip of FIG. 1.

FIG. 3 is a cross sectional view taken along the line 3-3 of FIG. 1 and viewed in the direction of the arrows.

FIG. 4 is an end view of the roofing clip of FIG. 1.

FIG. 5 is a top plan view of an alternate form of the roofing clip showing my new design.

FIG. 6 is a side view of the roofing clip of FIG. 5.

FIG. 7 is a cross sectional view taken along the line 7-7 of FIG. 5 and viewed in the direction of the arrows.

FIG. 8 is an end view of the roofing clip of FIG. 5.

The dominant features of my design reside in the longitudinally extending slot forming two legs for the clip and

the projection extending outward from the main body of the clip being aligned with the slot.

I claim:

The ornamental design for a roofing clip, as shown and described.
